CAP AND LATCH UNIT FOR PICTURE SCREEN HOLDERS

Laurel E. Cooley, Sr., and Laurel E. Cooley, Jr., La
Grange, and Carl O. Plaul, Chicago, Ill.

Application May 25, 1956, Serial No. 41,657

Term of patent 14 years

(Cl. D61—1)

FIG. 1.

FIG. 2.

FIG. 3.

FIG. 4.

FIG. 5.

Figure 1 is a perspective view of a cap and latch unit for picture screen holders showing our new design.

Fig. 2 is a side elevational view.

Fig. 3 is a top plan view.

Fig. 4 is an end view taken from the left of Fig. 1.

Fig. 5 is an end view taken from the right of Fig. 1.

We claim:

The ornamental design for a cap and latch unit for picture screen holders, as shown.
